Walter D. Edmonds

UNITED STATES PATENT OFFICE.

WALTER D. EDMONDS, OF BOONVILLE TOWNSHIP, ONEIDA COUNTY, NEW YORK.

PAPER SHEET AND METHOD OF MAKING THE SAME.

Application filed December 10, 1920. Serial No. 429,698.

To all whom it may concern:

Be it known that I, WALTER D. EDMONDS, a citizen of the United States, and a resident of the township of Boonville, in the county 5 of Oneida and State of New York, have invented a certain new and useful Improvement in Paper Sheets and Methods of Making the Same, of which the following is a specification.

10 My invention relates particularly to those well-known sheets of paper, containing a plurality of thereon inscribed similar units such as blank bank checks, stock certificates, postage stamps, etc. and composed usually 15 of fibrous material, portions of which have been cut out therefrom to form a plurality of alike mutually proximate circular perforations, disposed usually in a line, or row, dividing said units and along which the 20 sheet is usually severable by merely pulling it apart, thereby detaching one or more of said units from the remainder, and the objects of my invention comprise impartation to such sheets of more easy, certain and 25 accurate division, or severability, along their said lines, or rows, of perforations, this being of late years increasingly needed owing to the comparatively inferior paper and fibrous materials necessarily employed owing 30 to scarcity of better stock, the result being that the old time perforations prove too often inadequate to control the line of severance, or tear;— the paper owing to its comparative lack of required homogeneity and 35 cohesiveness, giving way or parting in directions angular to said rows.

In the accompanying drawings—

Figure 1 is a diagrammatic plan, or top, view of a sheet, or page, of a check book from 40 which the uppermost check has been removed.

Figure 2 is a like view of a corner of a part of the sheet, or page, shown in Figure 1, as it appeared before the said uppermost 45 check was removed, the scale being enlarged to more clearly show the merger of the creased lines in a corner perforation.

Figure 3 is, on still more enlarged scale, a perspective view of a fragment of the sheet 50 showing perforations and connecting crease as they appear before separation.

Figure 4 is, on still larger scale, a transverse section taken on the line 4—4 of Figure 3.

55 Figure 5 is a view similar to Figure 4 ex-

cept that the crease is made from the under, instead of the upper, side of the sheet.

I attain my objective as follows: I, preferably cut out of and remove from the sheet of paper, *s*, by any of the well-known, heretofore employed, procedures, portions thereof thereby making the familiar plurality of perforations, *p*, *p*, *p*, on any given, usually a straight, line between the units above referred to; and, in addition to this, either 60 simultaneously, or by a separate operation, I impart to the sheet, including, particularly, its component fibrous materials in exactly said line, and consequently wherever extending between said perforations, less strength, 65 i. e. less resistance to tear, than heretofore,— care being, of course, taken to thus not so greatly impair normal coherence as to induce breakage prior to intentional separation. This required, strictly local, comparative 70 weakness of the material where left between the perforations I impart thereto by procedures so well known that no particular description thereof is, I believe, required in order to understand and practice my invention. My line, or zone of novel relative weakness between the perforations is preferably 75 produced by simply creasing and thus compressing the material on a line coinciding with the mesne median line of the perforations. This crease, indicated by *c* in the drawings, can, as will be apparent to those skilled in the art, be imparted by suitably connecting the old perforating or cutting out instrumentalities with any usual creasing 80 device, for example a blade, or plurality of blades, not shown in the drawings, but so disposed, supported and adjusted that the pressure applied to actuate the usual perforating devices will serve simultaneously to 85 impress the creasers, or blades, sufficiently into the sheet to indent or compress, it between the perforations and to the required extent; or, of course, the perforations may be made in one operation, and thereafter the 90 creases in another.

The result is that the normal elsewhere thickness of the sheet is reduced between the perforations as plainly indicated in Figures 3, 4 and 5, and what is more important for 105 my purpose its constituent intervening fibrous material is weakened by being crushed, twisted or bent to such degree that it is there tearable, or breakable, much more readily than wherever elsewhere the sheet is 110

left uncreased, and this irrespective of the effect of the old perforations.

By this means, fractions, or parts, of the sheet which it is desired to withdraw therefrom for present use, for example that one, or more, of a plurality of postage, or other, stamps, blank checks, or the like, thereon printed, as indicated in Figures 1 and 2, can, by the usual manipulations, be torn, or severed, therefrom with substantially complete avoidance of the present above referred to too great risk of tearing into, or injuring, adjoining units.

It will be understood that my perforations connecting creases, *c*, *c*, are preferably impressed from the face, *f*, or printed side, of the sheet, as indicated in Figures 3 and 4, but they may be usefully indented from the reverse side, *r*, (Figure 5) or from both sides.

My invention not only facilitates and safeguards the tearing apart of the sheet as above described, but is also particularly useful in that it dispenses, if desired, with many of the perforations formerly required along a given line, in other words by aid of my crease, the sheet is readily severable, though the perforations be much more widely spaced apart than heretofore.

A notable and important feature of my invention is also its location of one of the perforations, for example *p'* (Figures 1 and 2) concentrically with the point at which two of my crease lines extending angularly to each other would intersect if thereto projected, this disposition greatly contributing to safe turning of the line of tear in the required direction.

I am aware that it has been suggested to merely fold a sheet of paper and provide it with a series of perforations along the fold in order to readily separate an opaque from a transparent portion of said sheet, the said folding thereof being for the purpose of superdisposing said two portions of the sheet in order to insert and impress them simultaneously in a typewriter. This I do not claim as my invention, it being distinguishable not only because failing to compress, i. e. crease, indent, or otherwise reduce the thickness of the sheet between the perforations, but also because such mere folding on the line of perforations is more or less deleterious, and altogether impracticable, for my purposes when the sheet contains two intersectant lines of perforations as is usually required.

Having now described my invention, what I claim as new and desire to secure by Letters Patent is the following, viz:

1. A paper sheet containing a row of perforations, the thickness of the sheet being between said perforations, and throughout the median line of said row, less than in other parts of said sheet.

2. A paper sheet containing a row of perforations the constituent material being compressed throughout the median line of said row.

3. A sheet containing a row of perforations and a line of continuous compression or indentation extending from one perforation to the next nearest thereto perforation.

4. A paper sheet containing a plurality of perforations disposed in one row, and another plurality of perforations disposed in another row, the said rows being mutually intersectant and the paper between said perforations being along said lines continuously compressed from one into the other of mutually adjacent pairs of said perforations.

5. A paper sheet containing a plurality of perforations disposed in one line, and another plurality of perforations disposed in another line, the said rows being mutually intersectant, one of said perforations being concentric with the point at which said lines, or rows, would, when thereto projected, intersect and the paper between said perforations being along said lines continuously compressed from one into the other of mutually adjacent pairs of said perforations.

6. The method of treating a sheet of paper which comprises making therein a plurality of perforations along a given line and also compressing the paper between said perforations.

7. The method of treating a sheet of paper which comprises making therein a plurality of perforations disposed in one line, and another plurality of perforations disposed in another line, the said rows being mutually intersectant, and then diminishing the thickness of the paper between the mutually adjacent perforations.

8. A paper sheet comprising a plurality of therethrough spaced-apart openings from the edges of which, in the plane of the sheet, portions of the paper have been completely severed and removed, the remaining portions of the paper extending between said openings are of less coherence than the remainder of the sheet.

WALTER D. EDMONDS.
